CLAIM

The ornamental design for an ear stent as shown and described.

DESCRIPTION

FIG. 1 is a perspective view of an ear stent showing a first embodiment of our new design;

FIG. 2 is a front elevational view of the ear stent of FIG. 1; FIG. 3 is a rear elevational view of the ear stent of FIG. 1; FIG. 4 is a left side elevational view of the ear stent of FIG. 1;

FIG. 5 is a right side elevational view of the ear stent of FIG. 1;

FIG. 6 is a top plan view of the ear stent of FIG. 1; FIG. 7 is a bottom plan view of the ear stent of FIG. 1;

FIG. 8 is a perspective view of an ear stent showing a second embodiment of our new design;

FIG. 9 is a front elevational view of the ear stent of FIG. 8; FIG. 10 is a rear elevational view of the ear stent of FIG. 8;

FIG. 11 is a left side elevational view of the ear stent of FIG. 8;

FIG. 12 is a right side elevational view of the ear stent of FIG. 8;

FIG. 13 is a top plan view of the ear stent of FIG. 8; and, FIG. 14 is a bottom plan view of the ear stent of FIG. 8.
